OARLOCK

John Gordon Sparkes, Great Neck, N. Y.

Application April 16, 1940, Serial No. 329,865

3 Claims. (Cl. 9—26)

This invention relates to oar locks for row boats and the like, and has as its principal object a design of an oar lock which will readily receive the oar, but once received will hold it in position during all normal working conditions.

Likewise, the design is of such a nature that the oar may be readily removed from the lock by the same path through which it was inserted.

In the usual types of oar locks, the lock consists essentially of a ring member mounted upon a post which is in turn mounted in a socket fastened to the side of the boat, thereby forming a swivel joint. The ring is usually opened at the top and each side thereof terminates in a diverging horn which permits the entry of the shaft of the oar. The difficulty with this type of oar lock is that the diameter of the ring is usually larger than it should be for the shaft of the oar, and the opening in the top of the ring must be as large as the shaft of the oar in order to permit entrance of the oar. This results in a compromise of dimensions, which produces an oar lock that does not retain the oar as it should, and furthermore permits of the slipping of the oar from the lock should the oar be tilted at an angle greater than the normal rowing position. The result is that an inexperienced person attempting to row a boat will invariably have difficulty in retaining the oar in the lock.

The present invention contemplates the use of a special shape, wherein the shaft of the oar enters the working position of the oar lock through a circuitous path, and once reaching this position, is held therein under all normal loads. The design is of such a shape that it allows entire freedom for the oar to any angle which may be required in the rowing operation. Furthermore the design is of such a nature that it will retain the oar should it be released entirely by the hand of the boatsman, and thereby prevent the oars falling overboard.

In order to more clearly disclose the invention, reference is made to the accompanying drawing, in which:

Figure 1 is an elevation showing a boat with the oar lock attached thereto.

Figure 2 is a perspective view showing the oar lock mounted in a bearing bracket and the oar resting therein.

Figure 3 is a plan view of the oar lock showing the various positions acquired by the shaft of the oar in entering or removing from the lock.

Similar reference numerals refer to similar parts throughout the drawing.

In the drawing, 1 is a boat, 2 is a bracket attached thereto by suitable fastenings 3. 4 is a boss formed on the bracket. 5 is a hole through the boss, adapted to receive the shank 6 of the oar lock. At the top of the shank 6 is formed a bearing hub 7, and to which is integrally attached a horn 8 and a horn 9. The horn 8 with horn 9 forms a semi-circular ring 10, adapted to engage the shaft 11 of an oar. The horn 9 extends upwardly and terminates in a knob 12 which is formed on the inner surface thereof. This knob 12 acts as a stop against which the shaft 11 of the oar will strike when moved upward along the horn 9. The inner face of the horn 8 extends upward from the circular face 10, to a point 13 which is approximately even with the top of the oar shaft when set against the surface 10. From this point, the inner surface of the horn 8 is extended away from the stop position 12 on horn 9 approximately along the circumference of a circle struck from the center of the stop 12, and then terminates in approximately a vertical position.

It will be seen by reference to Figure 3 that the shaft 11 of the oar may enter the lock by passing between the inner surface of the stop 12 on horn 9 and the inner surface 14 of the horn 8, whereupon it enters between the straight walls 15 and 16 of the horns 8 and 9, and rests against the semi-circular ring surface 10. Obviously, to remove the oar, the shaft 11 must follow through exactly the reverse direction.

When the oar is in use, the propelling force against the oar lock may be applied against either horn 8 or horn 9, as in each instance the stop 12 acts to prevent the oar from being pulled out of the lock.

It is to be noted that inasmuch as the oar lock is always above the surface of the water, that the oar when under load, that is when rowing to push the boat, is always at an angle sufficient for the blade to reach into the water. This means that the shaft of the oar is never parallel to the water when under load, therefore some part of the shaft is in close proximity to the stop 12, which would cause any further upward movement of the shaft to be stopped before the contact of the shaft moved above the surface 13. It will thus be seen that inasmuch as there is no load on the oar while it is in a horizontal position, that there is no tendency to move out of the lock, and the entire tendency to move out is at a time when the shaft is at an angle to the hori-

zontal. For this reason, the oar when loaded is always locked within the oar lock by the stop 12. Conversely, it is only necessary to bring the oar to a horizontal position in order to remove it from the lock.

It is obvious that the principles of the invention may be adapted to many types of locks and mountings without departing from the scope thereof.

Having described the invention, what is claimed as new and is desired to be secured by Letters Patent, is:

1. An oar lock of the open U type for boats, comprising a U shaped member adapted to be attached to a boat, the said U shaped member comprising upwardly extending arms forming therebetween a socket for receiving the shaft of an oar, one of the said arms terminating in a stop extending into and partly closing the socket, the other arm being cut away at a position opposite the said stop to compensate for the offset of the stop and to thereby admit the shaft of an oar.

5 2. An oar lock of the open U type for boats, comprising a U shaped member adapted to be pivotally attached to a boat, the said U shaped member comprising upwardly extending arms forming therebetween a socket for receiving the shaft of an oar, one of the said arms terminating in a stop extending into and partly closing the socket, the other arm being cut away at a position opposite the said stop to compensate for the offset of the stop and to thereby admit the shaft of an oar.

10 3. An oar lock of the open U type for boats, comprising a U shaped member adapted to be pivotally attached at its center to a boat, the said U shaped member comprising upwardly extending arms forming therebetween a socket for receiving the shaft of an oar, one of the said arms terminating in a stop extending into and partly closing the socket, the other arm being cut away at a position opposite the said stop to compensate for the offset of the stop and to thereby admit the shaft of an oar.

JOHN GORDON SPARKES.
